UNITED STATES PATENT OFFICE.

RICHARD A. JACKSON, OF PITTSBURG, PENNSYLVANIA, ASSIGNOR TO HIMSELF, JOHN A. KURTZ, AND SAMUEL GISSINGER, OF SAME PLACE.

IMPROVEMENT IN WEATHER-STRIPS FOR WINDOW-SASHES.

Specification forming part of Letters Patent No. 125,958, dated April 23, 1872; antedated April 3, 1872.

Specification describing certain Improvements in Strips for Window-Sash, invented by RICHARD A. JACKSON, of Pittsburg, in the county of Allegheny and State of Pennsylvania.

My invention relates to providing window-sash with tubular strips of gum, which are used in combination with a gum roller pivoted in the side of the sash-frame, as hereinafter described.

Figure 1 is a side elevation of a window-sash and its frame. Fig. 2 is a transverse section of the same at line *y* of Fig. 1.

A is the sash-frame; *B*, the sash, which is provided at each side with tubular strips *C*, of gum, which are embedded into grooves in the sides of the sash *B*, so that about one-half of the tubular strip will be buried in the frame,

the ends being secured and sealed to make them air-tight. *D* is a gum roller pivoted in the frame, and is used, in combination with the tubular strips *C*, for holding the sash in any desired position with relation to the frame.

Excluding air, preventing the rattling of the sash in frame, and holding the sash in any desired position with relation to the frame are the advantages of my improvement.

What I claim is—

The combination of the tubular strip *C* and roller *D* with the sash *B* and its frame *A*, as herein described.

R. A. JACKSON.
